CLAIM

The ornamental design for a sneaker, as shown and described.

DESCRIPTION

FIG. 1 is a front view of a sneaker, showing my new design; FIG. 2 is a rear view thereof; FIG. 3 is a right side view thereof; FIG. 4 is a front perspective view thereof; FIG. 5 is a top view thereof; FIG. 6 is a left side view thereof; FIG. 7 is a bottom view thereof; FIG. 8 is a bottom perspective view thereof; and, FIG. 9 is a top perspective view thereof.

The broken lines in the drawings illustrate the portions of the sneaker, which form no part of the claimed design.

1 Claim, 9 Drawing Sheets
